FOLDING OUTDOOR ANTENNA

Milton Spirit, Jamaica, and Jerome Goldman, New York, N. Y.; said Goldman assignor to said Spirit

Application June 11, 1954, Serial No. 436,074

9 Claims. (Cl. 343—818)

The present invention relates to antennae for the reception of high frequency signals, and more particularly to signals lying in two distinct spaced frequency bands, such as channels 2 to 13 of the present frequency allocation for television channels.

An object of the invention is to provide a unitary antenna structure comprising elements dimensioned for resonance in two separate frequency ranges.

A further object of the invention is the provision of a parasitic reflector element for each frequency band, each reflector being positioned for cooperation with the signal receiving elements for one of the bands of signal frequencies.

Still another object of the invention is the provision of a pair of high frequency signal receiving elements forming a generally U-shaped configuration and having arm portions connected to a pair of low frequency signal receiving elements in such manner that a common transmission line may be connected to both pairs of signal receiving elements at a single pair of antenna output terminals.

Another object of the invention is the provision of a mid-band parasitic resonator for the higher frequency band disposed in close proximity to the high frequency signal receiving elements for improving the efficiency of reception of the high frequency signals.

A further object of the invention is the provision of an antenna of this character which may be folded for shipment and readily unfolded for installation, the several antenna elements being securely positioned in either the folded or unfolded position.

Other and further objects, features and advantages of the invention will become apparent upon reading the following specification together with the accompanying drawing forming a part hereof.

Referring to the drawing:

Fig. 1 is a front view in elevation of an antenna embodying the invention mounted upon a vertical pipe support;

Fig. 2 is a side elevational view of the antenna of Fig. 1 in folded condition;

Fig. 3 is a plan of the folded antenna shown in Fig. 2;

Fig. 4 is a perspective view of an unfolded antenna mounted in operating position on a vertical pipe support;

Fig. 5 is an enlarged fragmentary sectional view in elevation taken along the line 5—5 of Fig. 4, looking in the direction of the arrows;

Fig. 6 is an enlarged fragmentary perspective view showing an inner end portion of one of the low frequency signal receiving elements locked in a laterally extending position as shown in Fig. 4;

Fig. 7 is an enlarged fragmentary sectional view in side elevation taken along the line 7—7 of Fig. 4, looking in the direction of the arrows;

Fig. 8 is an enlarged fragmentary sectional view in front elevation taken along the line 8—8 of Fig. 7, looking in the direction of the arrows.

2

Referring to Fig. 1, the antenna comprises a pair of aligned hollow tubular low frequency dipole elements 11 and 12 for the reception of signals in the lower frequency band. The free outer ends of hollow tubular dipole elements 11 and 12 are shown crimped at 13 and 14, respectively. The inner ends are crimped flat at 15 and 16, respectively, and are secured by rivets 17 and 18 to an upper insulating plate 19. The low frequency dipole elements are pivotally connected to the insulating plate 19 by the rivets 17 and 18, but the connections are relatively tight and produce frictional forces which oppose this pivotal movement, such pivotal movement being required only when folding or unfolding the antenna. In this manner, any looseness which might cause undesirable relative movement of the antenna elements is avoided. A certain residual amount of resiliency in the crimped flattened ends at 15 and 16 is advantageously provided to maintain this tight pivotal mechanical connection, notwithstanding dimensional variations accompanying changes in ambient temperature.

The insulating plate 19 is fixedly secured to the front end of a central supporting member 20 by rivets 21. Intermediate the ends of central supporting member 20 there is provided a supporting clamp comprising a U-bolt 22 (Figs. 3 and 4) having threaded leg portions which pass freely through apertures formed in central supporting member 20 and through corresponding apertures formed in a bearing plate 23. The U-bolt 22 secures the central supporting member 20 to an upright supporting pipe 24 (Fig. 4) by tightening nuts 22a on the threaded legs of the U-bolt 22, thereby gripping pipe 24 between the closed end of U-bolt 22 and bearing plate 23.

A reflector consisting of laterally extending reflector elements 25 and 26 (Fig. 4) is provided behind the low frequency dipole elements 11 and 12. The length of each low frequency reflector element 25, 26 and each low frequency dipole element 11, 12 is about one-quarter of a wavelength at the center frequency of the low frequency band. The reflector 25, 26 is spaced at about one-quarter of a wavelength behind the lower frequency band receiving dipoles 11, 12 at the center frequency of the low frequency band.

The reflector elements 25 and 26 are secured to a rear supporting plate 27 formed of electrically conductive material, being pivotally secured to supporting plate 27 by rivets 30 and 31, respectively. Rivets 30 and 31 provide pivotal and frictional connections as described above for rivets 17 and 18 which secure dipole elements 11 and 12 to the upper insulating plate 19. Rear supporting plate 27 is fixedly secured to the rear end of central supporting member 20 by a pair of rivets 32 and 33.

A pair of coupling elements 35 and 36 extend laterally outwardly from a lower insulating plate 37 disposed below the upper insulating plate 19. The coupling elements 35 and 36 are aligned and extend horizontally outwardly from the lower insulating plate 37 with inner portions which are generally parallel to the dipole elements 11 and 12. They then curve smoothly upwardly in a symmetrical manner to form relatively short vertically extending outer end portions 39 and 40 which extend toward and are connected to the dipole elements 11 and 12, respectively, intermediate the ends of each dipole element and inwardly of its midpoint. As shown in Fig. 5, the upwardly extending end portion 39 of coupling element 35 is connected to dipole element 11 by a strap 41 which is secured at its upper end by a bent tongue 42 which projects through a cooperating slot formed in the flattened upper end 43 of coupling member 35. The strap 41 is permanently secured to flattened upper end 43 by a rivet 44, thus securely

and permanently connecting the outer end portion 39 of the coupling element 35 both mechanically and electrically to the dipole element 11. The outer end 40 of the other coupling element 36 is similarly connected to the other dipole element 12.

At their adjacent inner ends, the coupling elements 35 and 36 are connected to the under side of lower insulating plate 37 by rivets 45 and 46, respectively, which provide both a pivotal and a frictional connection as described above for dipole elements 11 and 12.

The inner end portions of coupling elements 35 and 36 are flattened and bent downwardly, inwardly of rivets 45 and 46 to provide vertical downwardly extending line terminal ears 47 and 48 (Fig. 8). The terminal ears 47 and 48 are shown provided with binding post terminals comprising bolts and wing nuts 49 and 50 to which a transmission line 51 is shown connected, the transmission line 51 extending to a receiver or other signal utilization device (not shown).

The dipole elements 11 and 12 are dimensioned to be resonant to provide signal sensitivity at a frequency within a first frequency band which, in practice, will be the range of channels 2 to 6. The coupling elements 35 and 36 are dimensioned to be resonant to provide signal sensitivity at a frequency within a second and higher frequency band, the dipole elements 11 and 12 being relatively ineffective at these higher frequencies. In practice, the second frequency band will ordinarily cover the range of channels 7 to 13. The transmission line 51 is thus connected to the dipole elements 11 and 12 through the coupling elements 35 and 36 which are relatively ineffective at the resonant frequency of dipole elements 11 and 12.

The lower insulating plate 37 is connected to the forward end of central supporting member 20 by means of a C-shaped bracket 52 (Fig. 7). The upper end of C-shaped bracket 52 is fixedly secured to the forward end of central supporting member 20 by means of rivets 21 together with upper insulating plate 19. The lower end of C-shaped bracket 52 is rearwardly directed and lower insulating plate 37 is fixedly secured thereto by rivets 53, so that the upper and lower insulating plates 19 and 37 are fixedly held in vertically spaced relationship with respect to each other at the forward end of central supporting member 20.

A vertically adjustable L-shaped bracket designated generally as 54 is secured to C-shaped bracket 52 by a bolt 55 and wing nut 56. Bolt 55 passes through a vertically elongated slot 57 formed in the vertical upwardly extending leg 58 of L-shaped bracket 54. The lower horizontally extending leg 59 of L-shaped bracket 54 has an electrically conductive supporting plate 60 fixedly secured thereto by rivets 61. Extending laterally outwardly from supporting plate 60 are parasitic resonator elements 62 and 62 pivotally and frictionally secured to supporting plate 60 by rivets 63 and 64, respectively.

The parasitic resonator 62, 62 is resonant at around the mid-frequency of the higher frequency band. The adjustable coupling provided by the L-shaped bracket 54 permits the parasitic resonator 62, 62 to be moved toward or away from the horizontal portions of the coupling elements 35 and 36 to vary the tuning to a limited extent within the higher frequency band. The parasitic resonator 62, 62 serves to sharpen the resonance response characteristic of the coupling elements 35 and 36 thereby increasing their effective signal sensitivity in the higher band and reducing any tendency which they might otherwise have to interfere with the connection therethrough to the dipole elements 11 and 12 at frequencies in the lower band. Additionally, the parasitic resonator 62, 62 may be adjusted to be parallel to coupling elements 35 and 36.

Disposed transversely of central supporting member 20 at an appropriate distance behind resonator 62, 62 is a parasitic reflector member 65 for the higher frequency band. Reflector member 65 is upwardly curved interme-

diate its ends at 66 to pass over central supporting member 20 and prevent reflector member 65 from turning out of the position shown in Fig. 4. Reflector member 65 is secured to central supporting member 20 by a bolt and wing nut fastening device 67. Reflector member 65 may be turned to overlie central supporting member 20, as shown in Fig. 3, when the antenna is folded for shipment. Fastening device 67 is loosened and then tightened again for this purpose.

10 The antenna may be shipped in a folded condition, as shown in Figs. 2 and 3, and unfolded for installation in the laterally extended condition shown in Figs. 1 and 4. Clamping devices are provided which hold the antenna in the folded condition for shipment and which lock it in the 15 unfolded condition for permanent or temporary installation, as desired. The clamping devices comprise six clamp members 70 to 75, each held by a cooperating bolt and wing nut unit 76 to 81, respectively. Each clamp member comprises an apertured flat portion which is held against 20 one of the three plates 19, 27 or 60 by one of the bolt and wing nut units 76 to 81 which passes through the apertured flat portion of the clamp member and a corresponding aperture in one of the plates. Each of the clamp members 70 to 75 further comprises an integrally formed U-shaped 25 portion which embraces one of the antenna elements holding it pressed against one of the plates and locked against pivotal movement.

In Fig. 4, clamp member 70 and wing nut unit 76 hold dipole element 11 locked in its laterally extended position. 30 As shown on an enlarged scale in Fig. 6, clamp member 71 and wing nut unit 77 hold dipole element 12 similarly locked in its laterally extended position. Clamp members 72 and 73 with their associated wing nut units 78 and 79 lock the low frequency reflector elements 25 and 26, respectively, each in the laterally extended position. Resonator elements 61 and 62 are locked in the laterally extended position by clamp members 74 and 75 and wing nut units 80 and 81. No locking is shown for coupling 35 elements 35 and 36, since these elements are permanently clamped to dipole elements 11 and 12 and are thus held relatively immobile with respect to the dipole elements.

In the folded condition, the four clamp members 70 to 73 are turned to the positions shown in Fig. 3. The low frequency dipole and reflector elements 11, 12 and 40 25, 26 are folded toward each other, generally parallel to the central supporting member 20. Clamp member 70, 76 holds reflector element 25 in the folded position instead of dipole element 11 in the laterally extended position. Clamp member 71, 77 holds reflector element 26 in the folded position instead of dipole element 12 in the laterally extended position. Clamp 72, 78 holds dipole element 11 in the folded position. Clamp 73, 79 holds the other dipole element 12 in the folded position. Clamps 74, 80 and 75, 81 are not used in the folded 45 position, the elements of resonator 61, 62 being sufficiently short so that they are held by the frictional pivoting action of rivets 63 and 64 without the need for locking. Coupling members 35 and 36 are held in the folded position by their rigid connections to dipole elements 11 and 12, respectively.

It will be apparent to those skilled in the art that many changes and modifications may be made in the specific embodiment of the invention herein illustratively shown and described without departing from the scope of the 50 invention as defined in the appended claims.

What is claimed is:

1. An antenna of the class described, comprising: a pair of aligned laterally extending dipole elements resonant to provide signal sensitivity at a frequency within a first frequency band; a pair of aligned laterally extending coupling elements each comprising an inner portion extending generally parallel to one of said dipole elements and an outer end portion extending toward said dipole element and connected thereto intermediate the ends of 55 and inwardly of the midpoint of said dipole element, said

coupling elements being resonant to provide signal sensitivity at a frequency within a second frequency band at which said dipole elements are relatively ineffective and comprising frequencies appreciably higher than the frequencies of said first frequency band, and means for connecting a transmission line to said dipole elements through adjacent inner end portions of said coupling elements.

2. An antenna according to claim 1, further comprising parasitic resonator means resonant within said second frequency band and disposed in proximity to and parallel to said inner portions of said coupling elements for increasing the sharpness of resonance thereof.

3. An antenna according to claim 2, further comprising adjustment means for varying the spacing between said parasitic resonator means and said parallel portions of said coupling elements.

4. An antenna according to claim 1, further comprising reflector means for said dipole elements disposed rearwardly thereof; further reflector means for said coupling elements disposed rearwardly thereof; and common supporting means for said dipole elements, said coupling elements and both of said reflector means.

5. An antenna according to claim 4, further comprising parasitic resonator means carried by said common supporting means, said parasitic resonator means being resonant within said second frequency band and disposed in proximity to and parallel to said inner portions of said coupling elements for increasing the sharpness of resonance thereof.

6. An antenna according to claim 5, further comprising adjacent means for varying the spacing between said parasitic resonator means and said parallel portions of said coupling elements.

7. An antenna of the class described, comprising: elongated central forwardly and rearwardly extending supporting means; forward supporting means formed of insulating material and carried by said central supporting means; a pair of dipole elements pivotally secured to said forward supporting means and movable between laterally outwardly extending operative positions and folded positions adjacent to and generally parallel to said central supporting means; rear supporting means carried by said central supporting means; a pair of electrically interconnected

reflector elements pivotally secured to said rear supporting means and movable between laterally outwardly extending operative positions and folded positions adjacent to and generally parallel to said central supporting means; a pair of securing members carried by said forward supporting means and selectively engageable with said dipole elements to lock said dipole elements in their operative positions and with said reflector elements to lock said reflector elements in their folded positions; and a further pair of securing members carried by said rear supporting means and selectively engageable with said reflector elements to lock said reflector elements in their operative positions or with said dipole elements to lock said dipole elements in their folded positions.

8. An antenna according to claim 7, in which each of said securing member comprises a clamping member having a flat portion engageable with the particular supporting means by which it is carried and a U-shaped portion adapted to embrace a longitudinal portion of one of the antenna elements and press said portion of said antenna element into engagement with one of said supporting means for locking said antenna element against said pivotal movement, each of said securing members further comprising fastening means engaging said flat portion of said clamping member for drawing said flat portion into engagement with said particular supporting means and pressing said longitudinal portion of said antenna element thereagainst.

9. An antenna according to claim 8, in which said fastening means comprises two mutually engaging threaded members.
